UNITED STATES PATENT OFFICE.

EVERETT P. LARSH, OF DAYTON, OHIO.

SHORT CIRCUITER.

Application filed February 15, 1924. Serial No. 693,020.

To all whom it may concern:

Be it known that I, EVERETT P. LARSH, a citizen of the United States, residing at Dayton, in the county of Montgomery and State of Ohio, have invented certain new and useful Improvements in Short Circuiters, of which the following is a specification.

This invention relates to electric motors and more particularly to a short circuiting or operation changing device for automatically converting an alternating current motor from a repulsion starting condition to an induction running condition and vice versa in accordance with variation of speed.

The present construction embodies in a single structure the advantageous features of both the governor weight and garter spring type of short circuiting devices.

One of the purposes of the construction is to equalize the short circuiting movement of an annular series of independent radially movable contact members to effect the simultaneous engagement of all commutator bars.

One of the objectionable features of the garter spring type of short circuiter or one wherein the contact members operate against the yielding resistance of a flexible retaining and retracting element is the tendency for the contact members to move ununiformly. As the speed of rotation approaches the critical point at which the short circuiting devices are to operate, the tendency is to expand eccentrically or un-

uniformly against the resistance of the flexible retainer. The contact members of such short circuiters of the garter spring type being loosely mounted in an annular series, some of the members may be held more loosely than others, due to variation of the frictional contact or pressure laterally between succeeding elements of the series. The tendency is for such loosely held contact elements to move outward into engagement with the commutator bars in advance of the remaining contacts of the series.

While the contacts may expand initially at one point, the eccentricity is of course only momentary, and immediately afterward the remaining contacts will expand. Thus while the defect is objectionable, it is not vital. However, to meet certain conditions of use wherein precision and accuracy of operation is essential, and to conform to exacting trade requirements, and commer-

cial efficiency tests, it is quite desirable that the movement of the contact elements be equalized, and any loosely held elements be restrained until the more tightly held members of the series are brought into operative condition, so that all of the elements of the series may engage the commutator bars at exactly the same moment.

To this end the construction which embodies an annular series of centrifugally controlled contact members located adjacent to the lateral or terminal face of the commutator and concentric with its axis of rotation, are exteriorly beveled. A circumferential contractile band surrounds the beveled exterior faces of the annular series of contact members against the yielding resistance of which the members are radially movable into engagement with the commutator bars, under centrifugal influence. The particular feature in the present instance consists in interposing between the annular series of independent radially movable contact elements and the circumferential contractile retaining band an inflexible movable collar or equalizer, against which the contact members exert pressure in their outward or operative movement, and which in turn transmits the pressure against the yielding resistance of the circumferential contractile band.

The object of the invention is to simplify the structure as well as the means and mode of operation of such circuit changing devices, whereby they will not only be cheapened in construction, but will be more efficient in use, automatic in operation, uniform in action, automatically controlled and unlikely to get out of repair.

A further object of the invention is to provide such centrifugally controlled short circuiting means which will respond promptly to variations of speed above and below a predetermined rate of rotation.

A further and primary object of the invention is to provide a short circuiting or current changing device in which the movement of the operating elements will be equalized, while employing a flexible garter spring, or circumferential band, as the retaining or retracting element.

A further object of the invention is to provide such a short circuiting or current changing device which will be of compact form, containing few parts and no pivotal

joints or indirect movements, but in which the current controlling devices are directly operated by centrifugal tendency.

With the above primary and other incidental objects in view as will more fully appear in the specification, the invention consists of the features of construction, the parts and combinations thereof, and the mode of operation or their equivalents as hereinafter described and set forth in the claims.

In the accompanying drawings, wherein is shown the preferred, but obviously, not necessarily the only form of embodiment of the invention, Fig. 1 is a longitudinal sectional view of a motor commutator, to which the present form of short circuiting device has been applied. Fig. 2 is an end view thereof, with various parts broken away to expose underlying portions. Figs. 3 and 4 are sectional views similar to Fig. 1, illustrating modifications.

Like parts are indicated by similar characters of reference upon the several views.

The structure of the electric motor per se, forms no part of the present invention, which pertains wholly to the short circuiting means for the commutator bars, by which the motor is caused to operate alternately as a repulsion motor and an induction motor.

An alternating current, repulsion-induction motor of the single phase type to which the present invention is particularly adapted is one which as the name indicates, starts as a repulsion motor and as the speed approaches its normal or maximum rate of rotation automatically changes its character, and runs as an induction motor. Briefly described, it consists of a field or stator of laminated toothed construction having a single winding thereon connected to the supply circuit and a progressively wound armature or rotor with a commutator engaged by brushes during the starting or "repulsion" period together with speed controlled devices for short circuiting the armature windings through the commutator after the armature has attained a predetermined speed, which speed controlled means in some instances lifts the brushes from the commutator simultaneously with the short circuiting operation. There is no electrical connection between the stator and the rotor. The currents in the stator create an alternating flux which reacts on the rotor and induces its rotation. This type of motor, therefore, starts as a simple repulsion motor without compensating or auxiliary windings and operates as a repulsion motor until the rotor or armature approaches a synchronous speed or one commensurate with the windings, whereupon the speed controlled devices operate to automatically short circuit the armature winding through the commutator. Thus the motor is automatically trans-

formed from a repulsion type into an induction motor having what is essentially a squirrel cage rotor. It is the improvement of the speed operated governing or short circuiting device which forms the subject matter of the present invention. One of the advantages of a machine of this type is that it is inherently a constant speed motor having a high starting torque with low current consumption or minimum current surge.

The typical repulsion motor without compensation gives the most efficient starting torque possible while the single phase induction rotor with the squirrel cage armature or its equivalent affords, the most efficient motor when running.

A repulsion-induction type of motor combines these most desirable qualities in a single machine. As it possesses such high starting torque characteristics it is well adapted for operating machinery which starts under full load, as pumps, air compressors, grinding mills, and analogous installations. Requiring no starter, they are adapted for automatic control or distant operation. They start quickly and operate quietly and smoothly.

The above is offered merely to facilitate a thoro understanding of the purpose of the invention, and with no intent nor desire that it shall in any way be construed as limiting or restricting the application or scope of the invention.

Inasmuch as the construction of the motor per se forms no part of this invention, it has not been illustrated. It is to be understood, however, that the short circuiting means forming the subject matter hereof is applicable to various styles of motors of the character heretofore indicated. Referring to the drawings, 1 is the armature shaft, on which is carried the usual commutator comprising the core 2 about the periphery of which are located a continuous succession of commutator bars 3, insulated from the core 2 and from each other by intervening bodies of insulating material.

In the present instance, the commutator bars 3 are shown terminating flush with the core 2 and in a plane perpendicular to the axis of rotation, in Fig. 3. To the contrary in Fig. 1, the commutator bars 3 are shown projecting beyond or overhanging the face of the core 2, and inclined or beveled at their ends. It is obvious that the particular form or shape of the commutator bar is not an essential feature.

In the preferred embodiment of the invention as illustrated in the drawing, there is employed a disc 6 secured to the armature shaft 1, adjacent to, but in spaced relation with the face of the commutator. Located intermediate the disc 6 and the lateral face of the commutator is an annular series of

independent contact members 7. These contact members are slightly sector or wedge shape, and are assembled side by side in an annular series, in which each contact member is radially disposed in relation with the axis of rotation. Furthermore in such series, each independent contact member is laterally restrained and supported by the succeeding contact members of the series 10 and guided thereby in its radial movement. As shown in Fig. 1, each of the contact members is beveled or inclined on its outer extremity, thereby affording a tapered or conical exterior surface. Each of the contact members has been shown in Fig. 1 provided with an inwardly extending arm or lug 8, projecting within a concentric recess 9, in the lateral face of the commutator. The engagement of such projecting arms 20 or lugs 8 with the inner circumferential face of the recess 9 limits the outward movement of the contact members under centrifugal influence.

Circumferentially disposed about the inclined or tapered exterior of the annular series of contact members, is an elastic flexible retaining and retracting band 10. This band 10 preferably comprises a helical spring, the ends of which are interconnected 30 to form a continuous circular contractile member.

Upon rotation of the commutator and the series of contact members, centrifugal influence causes the contact member 7 to move outwardly in a radial direction against the yielding resistance of the circumferential contractile band 10. The contractile band 10 not only yieldingly resists the outward movement of the contact members 7, but 40 due to the inclination of the exterior margins upon which the contractile or retracting pressure is applied a camming action is exerted by which the contact members are pressed inwardly toward the commutator, 45 whereby as they move outwardly they have a wiping or sliding engagement upon the ends of the commutator bars.

As before mentioned, if the yielding resistance or spring tension of the contractile band 10 is applied directly to the individual contact member 7, some of the individual contact members which may be loosely held between their neighboring members will respond more quickly to the centrifugal influence and will move outward against the flexible yielding band, in advance of the main body of contact members. Such partial operation is prevented in the present instance by interposing between the series of contact members and the contractile band 10, an inflexible tapered or inclined collar 11, against the inner circumference of which the tapered margins of the contact members exert outward camming pressure and against the outer tapered

circumference of which the contractile band 10 exerts its retractive pressure. The outer periphery of this tapered collar 11, extends in diagonal or angular relation with the plane of the disc 6. The contractile band 10 is seated within the tapered groove or recess formed by the divergent relation of the disc 6, and the interposed inflexible collar 11. The contractile or camming action of the circumferential band or spring 70 10 tends to press the tapered collar 11 axially inward toward the commutator, and against the tapered outer margins of the contact members. The contact members are thus subjected to pressure in two directions. 80 That is, inwardly in a radial direction toward the center of rotation, and laterally in an axial direction toward the commutator face. The outward camming pressure of the inclined ends of the contact members upon the interior surface of the tapered collar 11 tends to cam such collar axially away from the commutator and toward the disc 6. It is to be noted that the collar is so proportioned and is of such width that 90 when urged inwardly by the contraction of the external band or spring 10, it occupies a spaced relation with the disc 6. This clearance intermediate the tapered collar 11, and disc 6 permits its lateral movement 95 as the contact members 7 move outwardly. This lateral shifting movement of the tapered collar 11, under outward pressure of the contact members exerts an outward camming action upon the contractile circumferential spring 10, expanding the spring against the yielding resistance of which the tapered collar 11 moves laterally under the outward radial pressure of the contact members due to centrifugal influence. The 100 operated relation of the parts is shown by dotted lines in Fig. 1. The tapered collar 11 serves to restrain any loosely held contact members until the entire body of members 105 is subjected to sufficient centrifugal influence to cause their movement in unison. Likewise if the spring 10 is of unequal resistance throughout its extent possessing a 110 tendency to yield more easily at one point than at another, such condition is corrected by the interposed tapered collar 11. To the contrary, the interposed tapered collar serves to concentrate the entire resistance of the contractile band 10 upon any loosely held 115 slug or slugs, which might tend toward radial movement in advance of the others. It is obvious that before any contact member or group of contact members can move radially in advance of the main body of such members, such member or members must force the tapered collar 11 laterally against the retractive tension of the entire 120 circular band 10. Without such interposed inflexible tapered collar 11, there is a tendency 125 for the contact members to flex the 130

retaining band 10 locally or at one point only to accommodate such uneven expansion or advance movement of individual contact members. Such irregular or individual action of the contact members is prevented by the interposed collar 11.

In order that the contact members may rotate in unison with the commutator the disc 6 is preferably though not necessarily provided with inwardly projecting ears or lugs 12, at spaced intervals, which project between succeeding contact members of the annular series separating the series into groups and affording a driving connection which further tends to guide the contact members in their radial movement.

In Figs. 3 and 4 there is shown a modification, where in lieu of the annular tapered collar 11, previously described, there is employed an axially movable disc 13, having a tapered or inclined flange 14, projecting in divergent spaced relation with the disc 6. The contractile band or retaining member 10 is seated in the divergent groove or recess intermediate the inclined flange 14 and the disc 6, and by its contraction tends to urge the disc 13 inwardly toward the commutator face. The contact members 7' are located intermediate the movable disc 13, and the face of the commutator. These contact members 7', in their outward or radial movement, bear upon the inner inclined face of the flange 14, and exert an outward camming movement upon the disc 13, tending to move the disc axially away from the commutator, and in turn exert a camming influence upon the contractile band 10 expanding such band against its yielding resistance as the disc 13 approaches the disc 6. The function, operation and result of this construction is substantially identical with that shown in Fig. 1 and previously described. Fig. 4 illustrates the parts mounted in a unitary structure, applicable to and removable from the armature shaft without disassembly. The stationary disc 6 and movable disc 13 are carried upon the laterally projecting central sleeve or hub 15 of a third disc 16, which is normally positioned closely adjacent to the face of the commutator, the contact members 7' being interposed between the disc 13 and the disc 16. By such construction the short circuiting unit may be assembled independent of the motor and subsequently applied thereto, or removed therefrom at will, as a single integral structure.

In order that there may be driving engagement between the rotating parts and the contact members, the disc 16 may be radially beaded or grooved as may be desired, or such radial lineal configuration may be formed in the disc 13 to guide the contact members in their radial movement

and insure their rotation in unison with the commutator.

From the above description it will be apparent that there is thus provided a device of the character described possessing the particular features of advantage before enumerated as desirable, but which obviously is susceptible of modification in its forms, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect, and the invention, is therefore, claimed in any of its forms or modifications within the legitimate and valid scope of the appended claims.

Having thus described my invention, I claim:

1. In a short circuiter for motor commutators, an annular series of weights disposed concentrically and radially in relation with the armature shaft, and movable radially in relation thereto under centrifugal influence, a flexible contractile band circumferentially surrounding the series of weights against the tension of which the weights move radially under centrifugal influence to effect the short circuiting of the commutator, and a yieldingly mounted inflexible band interposed between the weights and spring restraining the unequal distension of the annular series of weights.

2. In a short circuiter for motors, an annular expandable and contractible series of centrifugally actuated weights an annular yielding tension spring against the resistance of which the weights move radially under centrifugal influence to effect the short circuiting of the motor armature, and an equalizing element interposed between the annular spring and the weights restraining the unequal distension of the annular series of weights.

3. In a short circuiter for electric motors, an annular expandable and contractible series of centrifugally actuated weights, an annular contractile band circumferentially surrounding the weights against the resistance of which the weights are radially movable under influence of centrifugal influence, to effect the short circuiting of the motor armature, and equalizing means additional to the circumferential band for yieldingly restraining ununiform movement of the weights.

4. In a short circuiter for electric motors, an annular series of centrifugally actuated

weights, radially movable under influence of centrifugal influence, to effect the short circuiting of the motor armature, said series of weights being peripherally beveled, and an inflexible tapered collar circumferentially surrounding the weights and engaging with the beveled peripheral face thereof, and tending to yieldingly restrain ununiform radial movement thereof, said collar being axially movable under the camming influence of the weights, and an expansible and contractible tension element resisting the lateral movement of the collar and expanded by the wedging action of the tapered collar under expanding influence of the weights.

5. In a short circuiter for motors, an annular series of centrifugally actuated weights, an axially movable abutment member engaged by the weights upon radial movement thereof and restraining unequal movement of said weights, said abutment member having an external tapered cam face, and a yielding tension member engaging the external tapered face of the abutment member to resist the axial movement thereof.

6. In a short circuiter for motor commutators, an annular series of centrifugally actuated weights, said weights being beveled to present an exterior inclined face divergent to the axis of rotation, an elastic contractile

band circumferentially surrounding the series of weights against the yielding tension of which the weights are radially movable under centrifugal influence to effect the short circuiting of the commutator, and a tapered collar also circumferentially surrounding the series of weights with which the beveled faces of the weights engage upon radial movement, said collar being laterally displaced by the combined camming action of the weights as the weights are distended against the tension of the contractile band.

7. In a short circuiter for motor commutators, an annular series of centrifugally actuated weights, an annular contractile band against the tension of which the weights are radially movable to effect the short circuiting of the motor commutator, and an axially movable tapered collar engaged by the weights upon radial movement tending to resist ununiform expansion of the series of weights, said tapered collar being exteriorly engaged by the contractile band and laterally displaced by the combined camming action of the weights during their radial movement against the tension of the contractile band.

In testimony whereof, I have hereunto set my hand this 28th day of January, A. D. 1924.

EVERETT P. LARSH.
